Patented Oct. 15, 1912.

UNITED STATES PATENT OFFICE.

THOMAS J. FEGLEY AND GEORGE O. LEOPOLD, OF PHILADELPHIA, PENNSYLVANIA,
ASSIGNORS TO NORTH BROS. M'FG CO., OF PHILADELPHIA, PENNSYLVANIA, A
CORPORATION OF PENNSYLVANIA.

MEANS FOR ATTACHING BLADES OF TOOLS TO HANDLES.

1,041,451.

Specification of Letters Patent. Patented Oct. 15, 1912.

Application filed February 28, 1910. Serial No. 546,372.

To all whom it may concern:

Be it known that we, THOMAS J. FEGLEY and GEORGE O. LEOPOLD, citizens of the United States, residing in Philadelphia, Pennsylvania, have invented certain Improvements in Means for Attaching Blades of Tools to Handles, of which the following is a specification.

The object of our invention is to so construct a screw driver that the shank of the tool will be rigidly secured to the handle. This object we attain in the following manner, reference being had to the accompanying drawings, in which,—

15 Figure 1, is a side view of a screw driver partly in section, illustrating our invention; Fig. 2, is a transverse sectional view on the line 2—2 Fig. 1; Fig. 3, is a transverse sectional view on the line 3—3 Fig. 1; Fig. 20 4, is a transverse sectional view on the line 4—4 Fig. 1; Fig. 5, is an enlarged view of a part of Fig. 1; Fig. 6, is a detached perspective view of the blade of the screw driver; Fig. 7, is a detached perspective 25 view of the plug which carries the blade, and Fig. 8, is a perspective view showing the shank of the blade mounted in the plug.

A is the blade of the screw driver having 30 notched portion a at one end. The surface a' of this notched portion is beveled, as shown in the enlarged view Fig. 5, so as to fit tightly against the beveled portion b' of the plug B. This plug is shaped as clearly 35 shown in Fig. 7 and has an enlarged head b which forms part of the ferrule of the tool. The shank of the blade A is recessed at a^2 , and the metal of the plug is driven into the recessed portion as illustrated at c Fig. 5, 40 locking the blade permanently to the plug. The blade is first driven tightly into the plug, so that the beveled surfaces a' and b' hold the two parts firmly together, and then the metal of the plug is forced into the 45 recess a^2 . Thus the shank is prevented from turning in the plug, owing to the contact of the two flat surfaces a' and b' and it cannot move longitudinally owing to the metal of the plug being forced into the recess, as 50 shown. The plug is preferably made with a transverse slot as shown, the base of this

slot forming the beveled portion b' , as shown.

On the plug is a series of longitudinal ribs e , and these ribs are formed in the present instance by squeezing the metal of the plug between two dies which are less in diameter than the diameter of the plug, causing the metal to be cut and forced into the position shown in Fig. 2. These ribs 55 may extend the full length of the plug or may be arranged at intervals, as desired; the purpose is to prevent the plug from turning in the handle.

D is the handle having a cavity d into 65 which the plug is driven; the ribs forming channels in the walls of the cavity as the plug is driven, so that after the plug is once in position it cannot turn in the handle. The handle is preferably provided with a 70 ferrule d' which is forced on to the end of the handle in the above manner.

By the above construction the plug is permanently secured to the blade by indenting the plug back of the head and when the plug 75 is driven into the handle, the ribs of the plug cut their way into the body of the handle; preventing the handle from turning on the plug. The handle extends over the depressed portion c of the plug, making a 80 neat and substantial screw driver. When the invention is used as a chisel or a gouge, the head of the plug takes the thrust of the handle, while the notched end of the blade takes the thrust of the plug. 85

It will be understood that while we have shown the blade in the form of a screw driver, the invention may be used in securing blades of other tools to handles, without departing from the essential features of 90 the invention.

We claim:

The combination of a blade having a notched and tapered end and having a recess some distance from the notch; a handle having a cavity therein and provided with a ferrule; a plug having a head at the outer end and having longitudinal ribs projecting from its body and having a seat formed by slotting the plug transversely; 100 said seat being beveled for the reception of the beveled end of the blade; the portion

of the plug directly back of the head extending into the recess in the blade, permanently securing the handle to the plug; the transverse slot and the depressed portion of 5 the plug being covered by the handle and the plug being prevented from turning in the handle by the longitudinal ribs thereon.

In testimony whereof, we have signed

our names to this specification, in the presence of two subscribing witnesses.

THOMAS J. FEGLEY.
GEORGE O. LEOPOLD.
